US0D1059267S

(12) **United States Design Patent** (10) **Patent No.:** **US D1,059,267 S**
(45) **Date of Patent:** **** Jan. 28, 2025**

(54) **POWER SUPPLY**

(71) Applicant: **Shenzhen SYD Network Technology Co., Ltd**, Shenzhen (CN)

(72) Inventors: **Xinkai Chen**, Shenzhen (CN); **Haining Liang**, Shenzhen (CN)

(73) Assignee: **Shenzhen SYD Network Technology Co., Ltd**

(**) Term: **15 Years**

(21) Appl. No.: **29/892,334**

(22) Filed: **May 17, 2023**

(51) LOC (15) Cl. **13-02**

(52) U.S. Cl.

USPC **D13/103**

(58) **Field of Classification Search**

USPC D13/103, 104, 107, 108, 119, 121, 123, D13/154, 173, 174, 199

CPC Y02E 60/00; Y02E 60/10; H02J 50/00; H02J 50/005; H02J 50/10

See application file for complete search history.

(57) **CLAIM**

The ornamental design for a power supply, as shown and described.

DESCRIPTION

FIG. 1 is a first perspective view of a power supply showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the power supply that form no part of the claimed design.

1 Claim, 9 Drawing Sheets
